UNITED STATES PATENT OFFICE

BRUNO NEGRINI, OF BOLOGNA, ITALY

MACHINE FOR THE MANUFACTURE OF CURLED BENDINGS AT THE LONGITUDINAL EDGES OF METALLIC STRIPS

Application filed August 9, 1929, Serial No. 384,676, and in Italy January 11, 1929.

The invention refers to a machine adapted to execute by the cold process, curled bendings at the longitudinal edges of metallic strips. The same substantially consists of two ranges 5 of bending rollers having a varying profile, every one of which executes the gradual bending of a longitudinal edge of the flat strip up to the required shape.

According to the invention the machine is so constructed that the distance between the two ranges of bending rollers may be changed at a time by means of a hand control so that the machine may be instantly adjusted for operation on strips of various width.

15 The machine of the invention is provided with a front train of rollers adapted for the smoothing of the strips to be curled to render it more adapted to the bending, and is also provided with a rear train of rollers for the 20 final rectification of the curled strips. This latter train may be inclined with respect to the axis of the strip in order to straighten the same, which is particularly necessary in the case of strips having the convolutions on the 25 opposite sides, which strips on issuing from the machine, have a tendency to become twisted.

In the drawings which show two different embodiments of the invention, particularly 30 designed for the manufacturing of slats for roller shutters:

Fig. 1 is a side elevational view, partly broken away, of the machine of the present invention;

35 Fig. 2 is an end elevational view seen from the delivery end of the machine;

Fig. 3 is a plan view of the machine of Figures 1 and 2;

40 Figures 4 and 5 show the bending rollers in a side and end view respectively as they are adopted in the machine according to Figures 1, 2 and 3;

Fig. 6 shows twelve metallic strips, as they are bent and curled by twelve subsequent 45 pairs of bending rollers;

Figures 7 and 8 are a side view and a plan view respectively of the machine in which is adopted another form of bending rollers;

50 Figures 9 and 10 are an end and a partial side view respectively of a machine with the

bending rollers according to Figures 7 and 8.

In these drawings 1 is a frame on which are supported two groups of bending rollers formed of pairs 2 and 3 each of which curls respectively one longitudinal edge of the 55 strip. The surfaces of each pair of superposed rollers are shaped to give to each edge of the strip a series of subsequent bendings, so that after having passed all the pairs of bending rollers it assumes a profile as shown 60 in Figure 6 last illustration.

In the form of construction of the machine of Figures 1 to 5, the bending rollers 2 and 3 are positively driven by toothed wheels; the strip is driven by the rollers across the 65 bending machine. The rollers 3 are rigidly mounted on the shafts 4 whilst the rollers 2 are keyed on said shafts, so as to allow their axial displacement, which is imparted them by the disk 5 which is in engagement with 70 their peripheral grooves 6. The disk 5 is mounted on the threaded rod 7 screwed in the threaded sleeve 8 rotatably arranged in the frame 1 and integral with the worm wheel 9. The worm wheel 9 is driven by the worm 75 10. The different worms 10 are mounted on one shaft 11 parallel to the side of the machine, and which may be operated through a pair of bevel gears 12 by a handwheel 13. It is obvious that in rotating the shaft 11 80 85 an axial displacement of the disks 5 will be effected with a contemporaneous entrainment of rollers 2.

In the form of construction shown in Figures 7 to 10, the bending rollers 2 and 3, the distance of which gradually decreases towards the discharge end of the machine, are loosely mounted on the vertical shafts 14 fastened on the sides 15 and 15' of the machine; the strips are advanced by the superposed feed rollers 16 and 17. The rollers 17 are provided with sleeves 19 keyed on the shafts 18 so as to be axially movable on the same. These sleeves are rotatably mounted in the side 90 15' and present collars 20, which collars, in displacing the side 15' towards the right or towards the left, take with it the sleeve. The side 15' is slidable upon guides 40 and may be displaced by the interposition of the 95 threaded bolts 21 screwed in the correspond-

ing taps of the side; these threaded bolts are formed as it is the case in the first example, one piece with the worm wheel 22, engaged with a worm 23, and these different worms 5 are mounted on a single shaft 24, which can be rotated through a pair of bevel wheels 25 by a hand wheel 26. These means allow also in this case the instantaneous adjustment of the machine side, in order to supply with 10 volutes metal strips of different width.

The machine according to the invention is also provided with a preliminary straightening device which straightens the strip before its admission to the machine in rendering it 15 at the same time more flexible for the bending operation. This device consists in a group of lower rollers 27, the axes of which are coplanar, and in a group of upper rollers 28, which are parallel to the lower ones and adjustable 20 in the vertical direction by connecting with the rods 29 with the eccentric disks 30. This straightening device is further supplied with an independent roller 31, by which the final adjustment of the strip is effected 25 before its entrance into the bending mill.

The machine is further supplied with a subsequent straightening device to straighten the strip already supplied with volutes. This device presents a frame 32, fastened upon the 30 main frame 1 of the bending machine, and carries lower rollers 33 and upper rollers 34, which have the shape of the strip supplied with volutes. In this device the upper rollers can be adjusted vertically with respect to the 35 lower rollers, so as to enable the exertion of pressure required upon the strip. The frame 32 can also be rotated around an axis corresponding with the axis of the strip; for this purpose the frame 32 is fastened upon the 40 frame 1 by threaded bolts 35 which penetrate cuts 36 upon the frame 32.

The drive of the machine is accomplished by means of the shaft 37, which carries the 45 bevel gears 38 engaged with the bevel gears 39 keyed on the shafts 4.

I claim:—

1. In a machine for the manufacture of curled bendings along the longitudinal edges 50 of metal strips, a section for the preliminary straightening of the blank, an intermediate section for the cold bending of the edges and a section for the final straightening of the metal strip supplied with bendings, the section for the bending being composed of two 55 groups of bending rollers of variable profile, one group of which is arranged in correspondence with one edge of the strip to be fed through the machine and a hand wheel arranged on the machine frame to effect contemporaneous instantaneous adjustment of one group of bending rollers with respect to the rollers of the other group.

2. In a machine for the manufacture of 60 curled bendings along the longitudinal edges of metal strips, a section for the preliminary

straightening of the blank, an intermediate section for the cold bending of the edges and a section which can be rotated and adjusted with respect to the axis of the strip for the final straightening of the metal strip supplied with bendings, the section for the bending being composed of two groups of bending rollers of variable profile one group of which is arranged in correspondence with one edge of the strip to be fed through the 70 machine, and a hand wheel arranged on the machine frame to effect contemporaneous instantaneous adjustment of one group of bending rollers with respect to the rollers of the other group. 75

3. A machine according to claim 2, characterized in this, that each group of bending rollers consists in a number of roller pairs with two superposed rollers per pair, these roller pairs besides bending the strip also effect the feeding of the strip through the 80 machine. 85

4. In a machine for the manufacture of curled bendings along the longitudinal edges 90 of metal strips, special feed rollers for feeding the strips through the machine, a section for the preliminary straightening of the blank, an intermediate section for the cold bending of the edges and a section that can be rotated and adjusted with regard to the 95 axis of the strip for the final straightening of the metal strip with curled edges, the section for bending and curling the edges of the metal strips being composed of vertical shafts and two groups of single bending rollers of variable profile, loosely mounted upon said vertical shafts, one group of said rollers being arranged in correspondence to one edge of the strip to be fed through the machine and a hand control associated with the other 100 group of bending rollers on the machine frame so as to effect the simultaneous adjustment thereof with regard to the rollers of the 105 first-mentioned group.

In testimony whereof I have signed my 110 name to this specification.

BRUNO NEGRINI.
